Primary Examiner — Robert M Spear
Assistant Examiner — Rhea Shields(74) *Attorney, Agent, or Firm* — Judy W. Chung(57) **CLAIM**

The ornamental design for an oral care implement package, as shown and described.

DESCRIPTION

FIG. 1 is a front perspective view of a first embodiment of the new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of a second embodiment of the new design;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines in FIGS. 1, 5, 11 and 13 represent the claimed tear strip. The oblique line shading 1, 2 5, and 6 is intended to show a transparent or translucent surface. The stippling shown in FIGS. 9, 10 and 12-14 is intended to show a contrast in appearance.
